UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

PULL SWITCH.

Application filed May 18, 1922. Serial No. 561,862.

To all whom it may concern:

Be it known that I, REUBEN B. BENJAMIN, a citizen of the United States, residing at Chicago, in the county of Cook and State 5 of Illinois, have invented new and useful Improvements in Pull Switch, of which the following is a full, clear, concise, and exact description, reference being had to the accompanying drawing, forming a part of 10 this specification.

My invention relates to pull switches.

One of the objects of my invention is to provide means for facilitating the installation of a pull switch mechanism in a canopy.

15 A further object of my invention is to provide an adjustable chain guide for the pull chain of a pull switch to enable the chain to be led in any desired direction, thereby facilitating its installation in a 20 canopy.

Further objects will appear from the detailed description to follow and from the appended claims.

In the drawings in which my invention 25 is illustrated—

Figure 1 is a vertical sectional view showing a pull switch mechanism installed in a ceiling canopy;

Fig. 2 is a vertical axial section showing 30 a pull switch mechanism installed in a side wall canopy;

Fig. 3 is a side view of the switch bracket and switch;

Fig. 4 is a section on the line 4—4 of 35 Fig. 3;

Fig. 5 is a top plan view of the switch bracket and switch;

Fig. 6 is a side view of the switch mechanism;

40 Fig. 7 is a side view of the other side of the switch mechanism; and

Fig. 8 is a section on the line 8—8 of 45 Fig. 7.

Referring now to the drawings in detail and first to the ceiling construction shown in Fig. 1, this comprises a pull switch 10, mounted on a switch bracket 11 in the canopy 12. One end of the switch bracket 11 is secured onto the fixture stud 13, a 50 fixture stem 14 being screwed into the other end of the switch frame.

The canopy 12 is provided with an opening at 15 through which extends the elong-

gated chain guide 16, which conducts the 55 pull chain 17 from the switch mechanism to the opening in the canopy.

In order to facilitate the installation of the switch mechanism in the canopy this chain guide 16 is made angularly adjustable with respect to the switch mechanism so that 60 it can be adjusted so as to pass through the opening 15 in the canopy. The chain guide 16 has a range of adjustment from the full line position to the dotted line position shown in Fig. 1. With this range 65 of adjustment it will be seen that the chain guide can be adjusted to accommodate itself to different canopies in which the hole for the passage of the chain may be differently arranged.

As shown in Figs. 1 and 8 this angular adjustment of the chain guide 16 is effected by mounting it on a curved bracket 18 mounted on the insulating base 19 of the switch. The curved bracket 18 is provided 70 with a slot 20 in which the chain guide 16 is adjustably mounted, the threaded shank 21 (Fig. 8) of the chain guide extending 75 through this slot and being threaded into a nut 22. By screwing the threaded shank 21 tightly into the nut 22, the chain guide 16 is firmly clamped in adjusted position on the curved bracket 18. In order to prevent the nut 22 from turning when the shank 21 is screwed into it, the bracket 18 is provided with a pair of flanges or side wings 23 which embrace the nut and prevent it from turning. In order to keep the nut 22 from dropping out when the shank is completely 80 unscrewed from the nut, the bracket is provided with a turned up end 24.

The bracket 18 is held in place on the insulating base 19 by means of a pair of screws 25 which also serve to hold the switch on the switch bracket, this construction being shown in Fig. 4, which shows the screws 25 extending through registering openings in the switch bracket 11, the curved bracket 18 and the insulating base 19, and threaded into anchorage brackets 26. These anchorage stampings 26 also serve as an anchorage for the screws 27 which hold the insulating cover 28 for the switch mechanism in place on the insulating base 19.

The switch mechanism shown may be of 105 any suitable type. As shown it comprises

a rotatable commutator 29 which controls the circuit between the two wiring terminals 30 and 31.

The construction shown in Fig. 2 is substantially the same as that just described, except that here the switch bracket 11 is screwed onto a fixture stud 13 seated in an outlet box 32. A canopy or cover 33 is provided for the outlet box, having an opening 34 through which the chain guide 16 extends. The chain guide is adjustable from the full line to the dotted line position shown in the figure, so that it can readily be adjusted to accommodate itself to differences in location 10 of the opening 34 in the canopy.

Having thus described my invention, what I claim as new and desire to secure by Letters Patent of the United States is—

1. The combination with a canopy having an opening therein, of a pull switch comprising an insulating base mounted in fixed position with respect to said canopy, a pull switch mechanism mounted on said insulating base, a pull member, and a guide for 20 said pull member adjustable with respect to

said insulating base, whereby it may be adjusted to bring the pull member out through said opening.

2. The combination with a canopy having an opening therein, of a pull switch comprising an insulating base mounted in fixed position with respect to said canopy, a pull switch mechanism mounted on said insulating base, a pull member, and an elongated 30 guide member for said pull member angularly adjustable with respect to said insulating base, whereby it may be adjusted to bring said pull member out through said opening.

3. A pull switch device comprising a fixed 40 insulating base, a pull switch mechanism mounted thereon, a pull member, and an elongated guide member for said pull member angularly adjustable with respect to said insulating base, whereby it may be adjusted to 45 lead the pull member in a desired direction.

In witness whereof, I have hereunto subscribed my name.

REUBEN B. BENJAMIN.
